UNITED STATES PATENT OFFICE.

FRANK WILCOMB, OF NORRISTOWN, PENNSYLVANIA, ASSIGNOR TO H. C. COLEMAN, OF NORRISTOWN, PENNSYLVANIA.

STOP-MOTION FOR KNITTING-MACHINES.

SPECIFICATION forming part of Letters Patent No. 766,305, dated August 2, 1904.

Application filed October 30, 1903. Serial No. 179,258. (No model.)

To all whom it may concern:

Be it known that I, FRANK WILCOMB, a citizen of the United States, residing at Norristown, Pennsylvania, have invented certain new and useful Improvements in Stop-Motions for Knitting-Machines, of which the following is a specification.

My invention relates to stop-motion and let-off mechanism for knitting-machines; and it consists in the features and combination and arrangement of parts hereinafter described, and particularly pointed out in the claims.

In the accompanying drawings, Figure 1 is a plan view of so much of a knitting-machine as is necessary for a clear understanding of my invention, parts being in section. Fig. 2 is a side view with parts broken away and parts being in section. Fig. 3 is a detail view in section with parts in elevation and parts omitted, said view being taken from a point at the right of Fig. 2. Fig. 4 is a view of a detail.

In carrying out my invention I have applied my patented form of stop-motion disclosed in Letters Patent of the United States No. 698,090, granted to me on April 22, 1902, to a machine known as the "Acme" or "Mayo," such application requiring special devices and a novel combination and arrangement of the same in order that the stop-motion mentioned may be associated with the let-off mechanism of said "Mayo" machine and whereby certain advantages accrue which will be hereinafter described.

I will first describe the let-off mechanism of the said known machine with which my invention is associated.

In the drawings, 1 represents a knitting-head of the known form. The movable parts of the knitting-head are driven through gearing 2 from a main shaft 3, suitably journaled—as, for instance, in a bracket 4. This driving-shaft carries fast and loose pulleys 5 5'. A belt-shifting fork 6 is carried by a block 7, 45 slidably mounted on a rod 8, extending out from the frame 9 of the machine. A spring 10 is arranged between the belt-shifting block and the frame to keep the block with the fork pressed toward the left, Fig. 1, and thus keep

the belt on the loose pulley 5'. The shifting-block is guided in its movement by a rod or bar 11, extending out from the side of the frame and engaging a groove 12 in the top of the block.

For operating the let-off fork against the pressure of the spring a rock-shaft 13 is provided in said machine, journaled in bearings 14 on the machine-frame and having a handle 15 for operating it. The shaft at its rear end has an arm 16 projecting inwardly when the parts are in the position shown in all the drawings and having pivotally connected thereto a link 17, the other end of which is pivoted to the belt-shipper block 7. The arrangement of parts is such that when the rock-shaft is turned to move the arm 16 into the position indicated in Fig. 3 said position will be maintained by the parts because the pivot-point of 16 will be level with or slightly below the center of the rock-shaft, and the tendency of the spring exerted through link 17 will be to hold the parts locked in this position.

All the parts thus far described are the same as those well known on the type of machine referred to, and I will now describe how my stop-motion and a brake are applied to such machines and associated with the let-off mechanism just described.

The stop-motion proper as shown herein is substantially the same as that above referred to. Briefly, it comprises a stop-motion head 18, supported on a standard 19, said stop-motion head containing mechanism controlled by either a feeler-finger 20 or a sweep 21, so that when either of these devices is operated the mechanism within the stop-motion head will cause a vertical rock-shaft 22 to be operated, the lower end of said rock-shaft being journaled in the bracket 23 and carrying a trigger 24, which will release a lever 25, pivoted to said bracket and arranged to be under tension of the spring 26.

I will now describe the devices and the combination and arrangement of the same which I have invented and through which the patented form of stop-motion and the known form of let-off mechanism are associated.

The lever 25 is connected by a link 27 to a carrier 28 in the form of a plate arranged to slide at its upper end on the rock-shaft 13 and guided at its lower end by a fixed rod 29, held 5 at its front end in a bracket 30, secured to the front of the frame, and at its rear end said guide-rod is supported in an ear 30' of a bracket 31, fixed to the frame in any suitable manner, as by the bolt or nut 32. This carrier-plate has thereon a let-off pin 33, consisting in the present instance of a conical form of pin so arranged that when the carrier-plate is moved toward the rear of the machine when the stop-motion proper operates and pulls on 15 the link 27 the let-off pin will strike a stud or screw 28^x on a collar 29^x, fixed on the rock-shaft by the said screw, and the rock-shaft will be turned through a sufficient arc to carry the point 16 above the horizontal plane of the 20 center of the rock-shaft, and immediately the spring 10 exerts its force, and thus shifts the belt from the fast pulley to the loose one. The parts in all the drawings are shown in the position assumed by them when the machine 25 is in operation.

The function of the let-off pin is simply to throw the arm 16 up slightly from the position shown in Fig. 3, so that the pull of the link 17 will throw the arm 16 up to the point 30 16', thus causing the let-off action to be performed.

I provide a brake to stop the revolution of the machine quickly upon the operation of the stop-motion and let-off. This brake comprises a fork 34, adapted to engage a part 35 on the drive-shaft 3, the said fork having its stem 37 guided in ears 36 of the bracket before described. Said stem has an arm 37^x fixed thereto, and a spring 38 surrounds 35 the shank or stem and constantly exerts its force, tending to press the brake shoe or fork against the shaft. The arm 37^x has a sliding connection also with a second guide-rod 39, held in ears 40 of the said bracket 31. To 40 the arm 37^x of the brake-stem is pivoted at 41 a link 42, which at its forward end is provided with a roller 43, bearing on a cam 44 on a rock-shaft 45, which rock-shaft is journaled in the bracket 30 and has a hand-lever 46 fixed thereon. The cam 44 has part of its periphery 44' concentric with the center of the shaft 45 and another part 44" flattened. The hand-lever 46 is also provided with an arm 47, which is connected with the carrier 28 by a link 48. When the knitting-machine is running normally, the parts will be in the position shown in the several views, the brake being off and being held off by the roller 43, bearing against the high part or concentric 45 portion 44' of the cam. As soon as the stop-motion operates and the link 27 is pulled the carrier-plate 28 will be operated, first putting in motion the let-off mechanism and then through link 48 and shaft 45 causing the cam 60 to present its low or flat portion to the roller 65

43, thus allowing the spring 38 to exert its force, moving the arm 37^x and forcing the brake shoe or fork against the brake-surface of the shaft. By operating the hand-lever both the brake-shoe and the carrier 28 are reset into normal position, ready for automatic operation.

The parts when operated as just described having rendered the machine inoperative, it will be impossible to start the machine again 75 unless the stop-motion is again reset. This is due to the fact that the let-off pin will prevent the belt-shifter from being set to start the machine so long as the stop-motion remains unset. In other words, the let-off pin remains 80 to obstruct the movement of the screw or pin 28^x until the carriage 28 is moved forward in setting the stop-motion. The brake also remains in action against the brake-surface of the shaft until the stop-motion is reset, for, 85 as before described, the brake is controlled from the carrier 28 and until it is moved forward upon the resetting of the stop-motion proper the brake remains effective.

I have devised my stop-motion with a view 90 to fitting it to the machine without altering the arrangement of parts existing in said machine. The let-off carrier is applied to the existing shaft 13, as is also the collar 29^x, and the new parts immediately associated 95 with the carrier lie close to the side frame of the machine and on the outside thereof, while the brake with its guiding and operating means lie close against the inner side of the side frame and operative connection between 100 the devices lying outside and those lying inside the frame is made through the rock-shaft before mentioned, extending across the front edge of the side frame.

The let-off device consists of the belt-shifting fork, though where in the claims I employ these terms I do so in a generic sense, meaning the device shown or any substantial equivalent thereof, and where I employ the term "brake device" I mean the brake-shoe or any substantial equivalent thereof.

I claim as my invention—

1. In combination with a let-off device, a reciprocating carrier, means carried thereby for operating the let-off device, stop-motion mechanism, and connections to said means on the carrier from the stop-motion mechanism, connections between the means on the carrier and the let-off device, the said operating means on the carrier being arranged to prevent resetting of the let-off device while the carrier remains in its operated position.

2. In combination with a let-off device, a reciprocating carrier, a pin on the carrier, connections between the said pin on the carrier and the let-off device, and stop-motion means connected with the said carrier, substantially as described.

3. In combination with a let-off device, a reciprocating device, a rock-shaft on which the 130

said device reciprocates, means for operating said rock-shaft from the reciprocatory device, connections from the said rock-shaft to the let-off device and stop-motion mechanism connected with the reciprocatory device, substantially as described.

4. In combination with a let-off device, a rock-shaft, connections therefrom to the let-off device, a reciprocatory device arranged to rotate the rock-shaft and stop-motion connections leading to the reciprocatory device, substantially as described.

5. In combination with a let-off device, a rock-shaft with connections to the let-off device, a carrier slidable on the said rock-shaft, a pin on the carrier and a projection on the rock-shaft to be operated by the pin for turning the rock-shaft, substantially as described.

6. In combination a let-off device, a rock-shaft with connections to the let-off device, a carrier slidable on the said rock-shaft, a pin on the carrier and a projection on the rock-shaft to be operated by the pin for turning the rock-shaft, said projection being adjustable, substantially as described.

7. In combination with a let-off device, a rock-shaft with connections therefrom to the let-off device, a carrier sliding on the rock-shaft at one end, a guide for the other end of the said carrier upon which it slides, a pin on the carrier, a projection on the rock-shaft and stop-motion means connected with the carrier, substantially as described.

8. In combination with a let-off device arranged outside of the frame of the machine, a brake device arranged on the inside of the frame, a reciprocatory carrier, connections to operate the let-off device from the carrier, said carrier being arranged on the outer side of the frame, said carrier and brake device moving parallel with the frame, a connection from the said carrier to the brake device on the inner side of the frame consisting of links on the outer and inner sides of the frame connected at the front thereof and a stop-motion connection leading to the carrier, substantially as described.

9. In combination with a let-off device, a reciprocatory carrier, connections between the carrier and said device for operating the same,

a brake device, a connection between the said carrier and brake device comprising a rock-shaft, a cam thereon, a link connected with the brake device and controlled by the said cam and a connection from the carrier to the rock-shaft, substantially as described.

10. In combination with a let-off device, a reciprocatory carrier, connections therefrom to the said device for operating the same, a brake device, a rock-shaft connected with the carrier, means connecting the said rock-shaft with the brake device and stop-motion mechanism connected with the carrier, substantially as described.

11. In combination with a let-off device, a reciprocatory carrier, connections therefrom to the said device for operating the same, a brake device, a rock-shaft connected to said brake device and to said carrier and a handle for operating the rock-shaft, substantially as described.

12. In combination with a brake device, a reciprocatory carrier, a rock-shaft connected with the carrier and with the brake device and stop-motion mechanism connected with the carrier, substantially as described.

13. In combination with a let-off device, a bracket to be secured to the frame, a brake device carried by the said bracket, a carrier, connections for operating the same, said carrier being guided by a part of the bracket and connections between the said carrier and the brake device and between the carrier and the let-off device, substantially as described.

14. In combination a let-off device, a rock-shaft having a connection thereto, a carrier slidable on said shaft, said rock-shaft and carrier being arranged on the outside of the frame, a brake device arranged inside the frame, a rock-shaft at the front of the frame, connections between said rock-shaft and the carrier and brake device respectively, and stop-motion mechanism, substantially as described.

In testimony whereof I affix my signature in presence of two witnesses.

FRANK WILCOMB.
